UNITED STATES PATENT OFFICE.

FINIS MCLEAN, OF VALLEY JUNCTION, IOWA.

TIE-PLATE.

1,231,038.

Specification of Letters Patent. Patented June 26, 1917.

Application filed April 5, 1917. Serial No. 160,003.

To all whom it may concern:

Be it known that I, FINIS MCLEAN, a citizen of the United States, and resident of Valley Junction, in the county of Polk and State of Iowa, have invented a certain new and useful Tie-Plate, of which the following is a specification.

My invention relates to tie plates adapted to be placed on the ties of a railroad beneath 10 the base of the rail.

The object of my invention is to provide a tie plate of simple, inexpensive and durable construction which is a combination plate adapted for use with either lag screws 15 or ordinary spikes.

More particularly it is my object to provide a tie plate having suitable openings to receive spikes at one side of the rail base, and an opening on the same side to receive 20 a lag screw, and having spaced therefrom suitable openings to receive spikes, one of said latter openings being elongated so that it may be used with rails of different weights, and to provide near said last described openings spaced openings to receive lag screws so arranged as to be used with 25 rails of different weights.

Still a further object is to provide such a combination plate having its upper surface 30 slightly inclined for inclining the rail slightly inwardly.

Still a further object is to provide such a plate having on its lower surface ribs arranged longitudinally of the rail and designed to be substantially beneath the outer 35 edges of the rail base for strengthening the plate on the lines of the greatest strain and for entering the tie for holding the plate against slipping.

With these and other objects in view, my invention consists in the construction, arrangement and combination of the various parts of the device, whereby the objects contemplated are attained, as hereinafter more 45 fully set forth, pointed out in my claims, and illustrated in the accompanying drawings, in which:

Figure 1 shows a top or plan view of a tie plate embodying my invention.

Fig. 2 shows an end elevation of the same with a rail thereon shown in section, and

Fig. 3 shows a vertical sectional view taken on the line 3-3 of Fig. 1.

In the accompanying drawings I have used the reference numeral 10 to indicate

generally the body of the plate which has a flat horizontal lower surface and a substantially flat upper surface 11, the central portion of which on which the rail rests 60 being inclined slightly from the horizontal, as clearly shown in Fig. 2.

On the upper surface of the tie plate 10 adjacent to the thickest portion thereof, is a longitudinal rib 12 which engages the 65 outer edge of the base 13 of a rail 14, as shown in Fig. 2. The plate is provided on its lower surface with a pair of spaced longitudinal ribs 15, preferably sharp-edged, adapted to sink into the tie 16 to prevent 70 movement of the plate and also adapted to reinforce the plate on lines substantially below the edges of the rail base where the strain on the plate is greatest.

The upper surface of the plate on which 75 the rail rests is provided with parallel grooves 17 extending across the plate from end to end, which simply serve to reduce the weight of the plate. At the same time thick portions of the plate are provided beneath 80 the shank or central portion of the rail and beneath the outer edges of the rail base.

Transverse grooves 18 may be provided in the upper surface of the plate for the same purpose of reducing the weight thereof. 85

Cut through the plate 10 and through the rib 12 are spaced angular spike holes 19, so arranged that the spike received in the holes 19 will engage and hold the rail, the base of which rests against the rib 12. Between the holes 19 is a round hole 20 extending through the plate and adapted to receive a lag screw, the head of which will engage the base of the rail adjacent to the rib 12. 90

Extended through the plate 10 between the rib 12 and the adjacent parallel edge of the plate is another hole 21 designed to receive a lag screw for locking the plate to the tie. 95

Viewing the plate as shown in Fig. 1, there is provided in the right hand portion thereof a hole 22 opposite one of the holes 19 a sufficient distance such that the base of a rail may rest between the holes 19 and 22. 100 The hole 22 is transversely elongated, and is so located that a spike driven through it and adjacent to its end nearest the hole 19, will properly engage the base of a small-sized rail or a rail of the minimum weight 105 used on the road which uses such plates. Some roads use as many as three sizes of

rails, and the hole 22 is long enough so that the spike could be driven therethrough for holding any of the different sizes of rails.

Opposite the other hole 19 and arranged 5 in the right hand portion of the plate as shown in Fig. 1, is a hole 23 also transversely elongated and so arranged that when a medium weight rail is used a spike driven through the hole 23 adjacent to the 10 end thereof nearest the opposite hole 19 will properly engage the base of such rail, and a spike driven through the outer part of the hole 23 will properly engage the base of a rail of the largest size used.

15 In the right hand portion of the plate opposite the hole 20 is a round hole 24 to receive a lag screw for fastening the rail of the smallest size used, and the plate is provided with another hole 25 spaced from the 20 hole 24 and adapted to receive a lag screw for engaging the base of a rail of the largest size used.

In Fig. 2 I have shown a rail 14 on the plate with lag screws 26 and 27 extending 25 through the holes 20 and 24 for locking the rail and plate to the tie.

My improved tie plate has a number of advantages. In the first place it may be used either with spikes or with lag screws, 30 as may be desired, and can be used for supporting rails of different sizes. Spikes can be placed in the holes 19 and the hole 22 for fastening a rail of the smallest size, and if desired a lag screw could be placed in the 35 hole 24, thereby fastening the rail at four points with relation to the plate. If a medium sized rail is used spikes could be placed in the holes 19 and 22 and 23, thereby holding the rail at four points. If a 40 large sized rail is used spikes could be placed in the same holes. Either the smallest or largest sized rails could be held exclusively with lag screws received in the holes 24 and 25.

45 The grooves 17 and 18 reduce the weight of the plate considerably, and yet leave its greatest thickness immediately under the center of the rail and the outer edges of the base of the rail, and the latter portions, 50 which are under the greatest strain, are reinforced by the ribs 15 which also serve to fasten the plate to the tie. The upper surface of the plate which supports the rail is also inclined from the part which supports 55 the outer portion of the rail base, downwardly and inwardly.

It is well known that the treads of the 60 wheels of railroads are coned or inclined from the horizontal, which construction assists in keeping the wheels on the track without the assistance of the flanges. The 65 inclination or taper or coning of the tread, of course, causes some greater wear on the wheel and rail than would occur if the wheel rested flat on the rail. It is believed that

if the rail were slightly inclined, as in the illustration shown in Fig. 2, there would be a reduction in the wear on the wheel and also on the rail.

Some changes may be made in the construction and arrangement of my improved tie plate, without departing from the real spirit and purpose of my invention, and it is my object to cover by my patent any such modifications or use of mechanical equivalents as may reasonably be included within the scope of my claims.

I claim as my invention:

1. A tie plate comprising a body having on its upper surface a rib arranged to engage one side edge of a rail base, angular holes extending through said rib and said body, and angular holes arranged spaced from and opposite said first described holes, being transversely elongated, and of different lengths, said base being provided with spaced holes designed to receive lag screws or the like for engaging the base of the rail on the side opposite said rib.

2. A tie plate comprising a body having on its upper surface a rib arranged to engage one side edge of a rail base, angular holes extending through said rib and said body, angular holes arranged spaced from and opposite said first described holes, being transversely elongated, and of different lengths, said base being provided with spaced holes designed to receive lag screws or the like for engaging the base of the rail on the side opposite said rib, and a round hole extending through said rib and said body for receiving the lag screw.

3. A tie plate comprising a body having on its upper surface a rib arranged to engage one side edge of a rail base, angular holes extending through said rib and said body, and angular holes arranged spaced from and opposite said first described holes, being transversely elongated, and of different lengths, said base being provided with spaced holes designed to receive lag screws or the like for engaging the base of the rail on the side opposite said rib, said body being provided with longitudinal ribs on its lower surface designed to be substantially beneath the edges of the rail base.

4. A tie plate comprising a body having on its upper surface a rib arranged to engage one side edge of a rail base, angular holes extending through said rib and said body, and angular holes arranged spaced from and opposite said first described holes, being transversely elongated, and of different lengths, said base being provided with spaced holes designed to receive lag screws or the like for engaging the base of the rail on the side opposite said rib, said body being provided with longitudinal ribs on its lower surface designed to be substantially beneath the edges of the rail base, and with

longitudinal grooves in its upper surface arranged to be on opposite sides of the shank of the rail and between said last described ribs.

- 5 5. A tie plate comprising a body having on its upper surface a rib arranged to engage one side edge of a rail base, angular holes extending through said rib and said body, angular holes arranged spaced from and opposite said first described holes, being 10 transversely elongated, of different lengths, said base being provided with spaced holes designed to receive lag screws or the like for engaging the base of the rail on the side 15 opposite said rib, and a round hole extending through said rib and said body for receiving a lag screw, the upper surface of said plate which is designed to support the rail, being inclined from said rib downwardly 20 toward the farther side of said plate.

6. A tie plate, comprising a body having on its upper surface a rib arranged to en-

gage one side edge of a rail base, holes extending through said rib, and said body, and holes arranged spaced from and opposite said first described holes transversely elongated. 25

7. A rail plate comprising a body having on its upper surface a longitudinal rib spaced from one side edge, the upper surface 30 of the body being inclined from said rib toward the other side edge, said plate having longitudinal ribs on its lower surface designed to be beneath the edges of the base of the rail and adapted to enter a tie, and 35 also to serve as reinforcements for the plate, said plate being also provided with longitudinal grooves in its upper surface designed to be on opposite sides of the shank of the rail and between said last described 40 ribs.

Des Moines, Iowa, March 10, 1917.

FINIS McLEAN.
